COMBINED MICROPHONE AND
STAND THEREFOR

Eugène J. Freeman, Studio City, Calif., assignor to Freeman Electronics Corporation, Los Angeles, Calif., a corporation of California

Filed June 3, 1963, Ser. No. 75,191

Term of patent 14 years

(Cl. D26—14)

FIG. 1 is a front, side and top perspective view of a combined microphone and stand therefor, showing my new design.

FIG. 2 is an opposite side elevational view thereof.

FIG. 3 is a top plan view thereof with the microphone and supporting post rotated to another position relative to the base of the stand.

The microphone grille is conventional and is continuous within the area as shown.

I claim:

The ornamental design for a combined microphone and stand therefor, as shown and described.
